UNITED STATES PATENT OFFICE.

GEORGE W. O'BRYAN, OF CAMBRIA, VIRGINIA.

MILL.

1,077,852.

Specification of Letters Patent.

Patented Nov. 4, 1913.

Application filed July 2, 1912. Serial No. 707,293.

To all whom it may concern:

Be it known that I, GEORGE W. O'BRYAN, a citizen of the United States, residing at Cambria, in the county of Montgomery and State of Virginia, have invented a new and useful Mill, of which the following is a specification.

This invention relates to machines for crushing and grinding corn on the cob, or other cereals, one of the objects of the invention being to provide a machine of this character the crushing member of which cooperates with means for facilitating the reduction of the material, said means being adjustable so as to regulate the time required for directing the material from the crushing to the grinding mechanism.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawings the preferred form of the invention has been shown.

30 In said drawings:—Figure 1 is a central vertical longitudinal section through a portion of the mill. Fig. 2 is a vertical transverse section through the crushing cylinder and adjacent parts. Fig. 3 is an enlarged 35 section through one side wall of the casing of the crusher and showing the adjustable blade. Fig. 4 is an inner elevation of said blade and the adjacent portion of the wall of the crusher casing.

40 Referring to the figures by characters of reference 1 designates the base frame of the mill, the same being provided with an end cross strip 2 on which is mounted a bearing member 4 which constitutes an extension 45 of the casing 6 of the crushing mechanism, this casing having flat parallel side walls 7 one of which is formed with crossed slots 8 adjacent each end for the reception of fastening bolts 9. These bolts extend from the 50 end portions of an inclined blade 10 and it will be apparent, by referring to Fig. 4, that by shifting the bolts 9 within the slots 8, the blade 10 can be held either horizontal or can be adjusted with either of its ends elevated.

Fitted in the open space formed between

the lower ends of the side walls 7 and secured to said walls is a plate 11 the upper face of which is concaved and ribbed. Journaled within the bearing member 4 is a 60 shaft 28 having a pulley 30 which constitutes means for driving the same. A hopper 31 opens downwardly into the space between the side walls 7 of the crusher casing. A revoluble crushing element 34 is 65 secured to the shaft 28 and has outstanding teeth 35 extending spirally around the shaft. These teeth are adapted to travel close to the free longitudinal edge of the blade 10 and coöperate therewith for the purpose of 70 crushing material supplied to the casing 6. One end of the casing 6 discharges through a ring 39 secured to the center of one side of a drum 40 which is fixedly mounted upon the base 1 and has a stationary circular 75 grinding member 42 mounted therein, there being a circular opening 43 at the center of said grinding member and registering with the passage through the ring 39. A revoluble grinding member 44 is secured to the 80 shaft 28 and is adapted to rotate within the drum 40. The adjoining or active faces of the grinding members may be formed with any suitable arrangement of burs and mounted on the shaft 28 and bearing against 85 the middle portion of the revoluble grinding member 44, is a sleeve 47 carrying a conveying blade or worm 48 whereby material, when discharged into the opening 43, will be directed by said blade or worm toward 90 the space between the two grinding members.

Cobs with corn thereon to be ground are deposited in the hopper and fall onto the crusher 34 where the teeth 35 engage the 95 cobs and carry them downwardly in the direction of the arrow shown in Fig. 2, these cobs being thoroughly ground upon the toothed concaved plate 11 and being finally brought upwardly against the blade 10. 100 Thus the material will be quickly reduced and will be gradually fed to the opening in the ring 39 and thence to the opening 43. At this point the blade 48 will engage the material and force it against the revoluble 105 grinding element 44 where said material will be free to gravitate into the space between the two grinding members. Before passing out from between these two members, the material will be reduced to a finely 110 comminuted state after which it will be discharged into the drum 40.

Attention is called to the fact that the blade 10 is adjustably mounted. When the blade has its cutting edge parallel with the axis of rotation of the shaft 28, it only 5 serves to facilitate the crushing of the material acted on by the teeth 35 of the crusher. However, should it be desired to feed the material more rapidly to the grinding members 42 and 44, that end of the blade 10 10 nearest the ring 39 is elevated while the other end of the blade is lowered. After securing the blade in this manner, it will be seen that the material, when carried toward the blade 10 by the teeth 35, will be deflected 15 ed along said blade and toward the opening in the ring 39. Thus the operation of grinding material will be greatly accelerated.

What is claimed is:—

1. In a mill, the combination with a cas- 20 ing including a concave, of a shaft mounted for rotation, a revoluble crushing element mounted on the shaft, a blade secured to

and extending longitudinally of one wall of the casing and coöperating with said ele- 25 ment, and means for raising or lowering either or both ends of the blade.

2. In a mill, the combination with a cas- 30 ing including a concave, there being an outlet at one end of the casing, of a revoluble crushing element within the casing, one wall having intersecting slots near each end thereof, a blade upon one wall of the casing and coöperating with the crushing element, and means extending from the blade and into the slots for raising or lowering either 35 or both ends of the blade and holding them in adjusted position.

In testimony that I claim the foregoing as my own, I have hereto affixed my signature in the presence of two witnesses.

GEORGE W. O'BRYAN.
